UNITED STATES PATENT OFFICE.

HARRY MARTIN, OF CHICAGO, ILLINOIS.

DESIGN FOR A RAINCOAT.

Application filed February 23, 1929. Serial No. 30,178. Term of patent 14 years.

To all whom it may concern:

Be it known that I, HARRY MARTIN, a citizen of the United States, residing at Chicago, in the county of Cook and State of Illinois, have invented a new, original, and ornamental Design for Raincoats, of which the following is a specification, reference being had to the accompanying drawings, forming part thereof.

The figure of the drawing is a front perspective view of a raincoat showing my new design, the same being illustrated on a figure illustrated in dotted lines.

I claim:

The ornamental design for a raincoat, as shown and described.

HARRY MARTIN.
